UNITED STATES PATENT OFFICE

170,936

GARDEN ROW MARKER

Edwin B. Pegram, Bozeman, Mont.

Application June 8, 1953, Serial No. 25,364

Term of patent 14 years

(Cl. D35—2)

To all whom it may concern:

Be it known that I, Edwin B. Pegram, a citizen of the United States, residing at Bozeman, in the county of Gallatin and State of Montana, have invented a new, original, and ornamental Design for Garden Row Marker, of which the following is a specification, reference being had to the accompanying drawing, forming part thereof.

Fig. 1 is a front elevational view of a garden row marker, showing my new design.

Fig. 2 is an edge view of the same.

Fig. 3 is a rear elevational view.

I claim:

The ornamental design for a garden row marker, as shown.

EDWIN B. PEGRAM.
